UNITED STATES PATENT OFFICE.

DAVID JOSEPH SMITH, OF LONDON, AND CHARLES TOWL, OF FOREST GATE, ESSEX, ENGLAND.

MEANS FOR AUTOMATICALLY OPERATING BULKHEAD DOORS AND SLUICE GATES.

1,416,070.

Specification of Letters Patent. Patented May 16, 1922.

Original application filed February 3, 1916, Serial No. 76,031. Divided and this application filed November 20, 1919. Serial No. 339,319.

To all whom it may concern:

Be it known that we, DAVID JOSEPH SMITH, a subject of the King of Great Britain, and a resident of Finsbury Park, London, N., 5 England, and CHARLES TOWL, a subject of the King of Great Britain, and a resident of Forest Gate, Essex, England, have invented Means for Automatically Operating Bulkhead Doors and Sluice Gates, of which the 10 following is the specification.

The invention relates to improvements in automatic door operating mechanisms, and constitutes a division of our co-pending application Serial No. 76031, filed February 3, 15 1916.

Many forms of apparatus have heretofore been used in operating doors for watertight compartments or bulkheads for vessels and the like, and these prior art devices have 20 been faulty in many respects, either due to the fact that the doors when released would not close in time, or the mechanism for releasing and closing said doors was of such a complicated nature as to be subject to injury during the pitching or rolling of the 25 ship, and therefore become jammed and of no value should an emergency arise in which the doors are to be closed.

The object of the present invention is to 30 provide means for automatically releasing and positively closing closure doors for watertight compartments for bulkheads of ships, or for operating automatically sluice gates or any other closure.

With this conception in mind, the invention 35 consists of an automatic generator adapted to produce pressure gases upon the admission of fluid thereto, the said generator being in communication with a cylinder 40 having a piston therein adapted upon a movement thereof in one direction to release detent means for holding a door in open position, and to also positively move said door to its closed position or approximately 45 thereto after the release of the detent mechanism.

In carrying out the invention the generator 50 may be placed in a position adjacent the door to be closed and the water upon entering the ship flows into the generator through a suitable valve producing the pressure gases that are instantly admitted to the cylinder, actuating the piston disposed therein, releasing the door trip mechanism upon

a slight movement of the piston, and upon 55 a continued movement thereof positively closing the door.

In the accompanying drawings we have shown the preferred embodiment of the invention, but it will of course be understood 60 that this disclosure is only for the purpose of illustration, and that other means can be utilized for releasing and closing the door, as soon as said means is responsive to the gas pressure generated in the automatic 65 generator.

Fig. 1 is an elevation of door-operating means constructed in accordance with the present invention, the operating mechanism being shown applied to a bulkhead door. 70

Fig. 2 is a detail part section and part side elevation, on an enlarged scale, of the detent and lock bolt.

Fig. 3 is a detail horizontal section, on an enlarged scale, of the detent and lock 75 bolt.

Referring now more particularly to the drawing, wherein like reference characters indicate corresponding parts, the numeral 1 designates a bulkhead door adapted to open 80 and close a suitable bulkhead or water tight compartment and disposed adjacent said door is a suitable cylinder 2 having closure plates 3 and 4 at each end thereof, the closure plate 3 being provided with an opening to receive the gas pressure pipe 5, and the closure plate 4 with a piston rod opening through which passes the piston rod 6 connected to the piston 7. The piston rod 6 is adapted to reciprocate in the cylinder 2, 90 and this rod has secured at its end a suitable head 8 carrying a transverse bolt or stud 9 which is adapted at one end to ride within an elongated slot 10 formed in the bulkhead door 1 upon the actuation of the 95 piston. The slot 10 does not extend through the door, but is only disposed therein and of a sufficient depth to receive the stud 9. The head 8 of the piston rod is formed with a projection or lug 11 along its end 100 adapted to be disposed within the path of a suitable bell crank lever 12 fulcrumed in a bracket 13 which is rigidly secured to the stationary wall of the bulkhead, the bracket being shown broken away, the other end of 105 the lever being pivotally attached to a locking detent or bolt 13' which is adapted to slide within a vertical guide arranged in

the metal guide 15 which is preferably a casting rigidly secured in any manner to a part of the vessel, but preferably to the bulkhead wall. The guide casting 15 has 5 also formed therein longitudinally a guide for the bolt or rod 16, having at one end an eye portion 17 which is pivotally connected to the door 1 by means of a pivot pin 17', it being here observed that when 10 the bell crank lever 12 is rocked the detent or locking element 13' is raised out of engagement with the bolt or rod 16 which permits the door to be moved by the piston from its open position, shown in full 15 lines Figure 1, to a closed position disclosed in dotted lines broken in the centre. The door 1 if arranged in any usual manner on rollers (not shown) to slide laterally, may have its movement assisted by being 20 arranged upon a decline indicated by the lines *a*, *b* in Fig. 1 of the drawing.

In the operation of doors of this character, it is highly desirable that they immediately close when the emergency arises 25 and it is also necessary that as little mechanism as possible be employed so that no failure will occur. To this end as a means for producing a medium for automatically operating the piston to release the door and 30 close same, we provide a generator 18 having a plurality of openings 19 for the entrance of water. A flap valve 20, of conventional form, is arranged behind the openings 19, said flap valve permitting the entrance of water through the openings 19 35 into the generator 18 but preventing pressure gases from discharging therefrom. The generator is provided with a detachable perforated receptacle 21 for carbide of 40 calcium or the like, in addition to the water passages 19. The generator is disposed preferably adjacent the bulkhead door which it operates, and when water rises a sufficient height to flow within the inlet openings 19 45 of the generator, gas is generated therein from the carbide and this gas immediately flows out under pressure through the discharge pipe 22 communicating with the cylinder 2 by the pipe 5, thereby moving the 50 piston therein and tripping the bell crank lever 12 during its movement by means of the lug 11, the continued movement of the piston when the part 9 engages the inner end of the slot 10 serving to positively move 55 the door after it has been released by the raising of the detent 13', the piston obviously being actuated by the pressure of the gases produced in the generator by the before mentioned means.

60 The locking detent or bolt 13' is mounted for a sliding movement within the guide

casting 15, while the pivoted bolt or rod 16 is formed with a suitable depression or recess into which said detent enters when the bulkhead door is in an open position as disclosed in Figure 1, and upon a raising of this detent the rod 16 is permitted to slide forwardly, thus allowing the door to close the same being positively closed by the piston rod when the stud 9 in the head 8 engages the end of the slot 10 after a portion of the movement of said rod, and this closing action is continued until the piston has made a full stroke which is sufficient to positively close the bulkhead door and prevent 75 the admission of water therethrough.

While the operation of the apparatus will be understood from the foregoing, it might be briefly stated as follows:

The door is normally open as shown in 80 full lines Figure 1. Should a leakage in the vessel occur, water will enter the same until it reaches a sufficient height to pass through the openings in the generator, instantly generating gases in the carbide 85 therein which gases are conveyed through the pipe 22 to the cylinder 2 moving the piston therein. The movement of this piston at once operates the bell crank lever 12, leaving the crank 13 and unlocking the door 90 from the walls of the bulkhead. The piston continues its movement under the influence of the pressure gases and when the stud 9 reaches the end of the slot 10, the continued movement of the piston serves to positively 95 move the door to closed position. While the present invention is shown as being applied to vessels for the operation of bulkhead doors, it will of course be understood that the same is applicable to any form of closure 100 where it is desirable to automatically and quickly operate a door or gate or the like, and we wish it to be understood that this invention is not limited to the application of the apparatus to vessels.

Having thus described the invention, what we claim is:

Means for operating a door or the like, comprising a cylinder having a piston therein, a generator, for automatically producing 110 pressure gases upon the introduction of water thereto, in communication with the cylinder, means for normally holding the door in an open position, said means being adapted to be actuated upon movement of the piston, to release the door, said door being moved to a closed position after the release of said holding means upon a continued operation of the piston.

DAVID JOSEPH SMITH.
CHARLES TOWL.
